CLAIM

The ornamental design for a fryer basket, as shown and described.

DESCRIPTION

FIG. 1 is a side elevation view of a fryer basket showing our new design, it being understood that the opposite side view is a mirror image thereof

FIG. 2 is a front top perspective view thereof;

FIG. 3 is a rear perspective view thereof;

FIG. 4 is a front elevation view thereof;

FIG. 5 is a rear elevation view thereof;

FIG. 6 is a top plan view thereof; and,

FIG. 7 is a bottom view thereof.
